[57] ABSTRACT

A device for raising a patient resting on a tabletop from a flat position to a desired angular position for aiding in photographic and examination procedures. The device, located beneath the patient, includes a flexible belt secured about the table and a lever pivotally attached to the belt at one end. A lever support means maintains the lever pivoted upwardly and the patient angularly positioned as desired.

3 Claims, 3 Drawing Figures

FIG. 1

FIG. 2

FIG. 3

PATIENT POSITIONER DEVICE

This invention relates generally to a device for aiding in various anatomical photographic and examination procedures and more particularly to such a device capable of angularly positioning a patient for more effectively carrying out such procedures.

While conducting various anatomical photographic and examination procedures with the patient in a horizontal position, it becomes essential that photographs be taken not only frontally but at angles thereby requiring that the patient be moved to afford the best possible position for the camera. The patient cannot be effectively propped into a proper position for the camera by an attendant or attendants without avoiding subsequent movement, especially during lengthy examination procedures. For example, a heart catheterization procedure is generally carried out by inserting a catheter into the artery in the area of the groin with consequent numerous pictures thereafter taken of the heart from various angles. In this procedure, it is necessary that the hips of the patient be constrained and that the spine then be twisted sufficiently to obtain the proper relationship between the camera and the heart to assure utmost clarity of the photos.

Previous devices in this field make use of either a rotating table or some type of upper body harness designed to give the attendant a better opportunity to position the patient. Such devices, however, often obstruct the camera so that it cannot be effectively placed in the most advantageous position. Moreover, many of these prior art devices are rather complicated in their design so that both capital expense and cost of operation become important factors.

In accordance with the present invention, a highly practical and economical device is provided for movement of the patient to a desired angular position and maintaining the patient propped in such position. This is the principal object of the invention.

Another object is to provide such device which is located beneath the patient and includes a flexible belt secured about the examination table with a lever being pivotally attached to the belt at one end. The patient may therefore be easily shifted into a desired angular position as the lever is pivoted upwardly.

A further object of this invention is to provide such a device wherein the lever is pivotally attached at one end to the top portion of the flexible belt near one side of the table with the free end of the lever extending outwardly of the other side of the table.

Other objects, advantages and novel features of the invention will become more apparent from the following detailed description of the invention when considered in conjunction with the accompanying drawings wherein:

FIG. 1 is a perspective view showing a patient lying on an examination table with a pair of positioning devices of the present invention located beneath his upper torso;

FIG. 2 is a sectional view taken along the line 2—2 of FIG. 1 showing operation of the positioning device; and

FIG. 3 is a sectional view taken along the line 3—3 of FIG. 1 without a showing of the patient.

Turning now to the drawings wherein like reference characters refer to like and corresponding parts throughout the several views, a patient P is shown in

FIG. 1 lying in a flat and horizontal position on the top surface of an examination table 10. This table includes a support surface 11, legs 12 and a foam or similar type of pad 13. The patient positioner device of the invention, generally designated 14, is located beneath the patient's upper torso so that this portion of the patient's body may be angularly adjusted in relation to the camera during a heart catheterization procedure, for example. During such procedure, the hips of the patient may be constrained as by means of a strap or belt, not shown in the drawings.

Device 14 is more clearly shown in FIG. 2 as comprising a flexible belt 15, of durable fabric or similar material, wrapped about the support 11 and pad 13 and secured in place as by means of a Velcro type fastener provided at the free end 16 of the belt. Of course, other types of securing means may be used as well; for example, a buckle, a clamp, snap fastener, etc.

A lever member 17 is pivotally attached at one end to the top surface 18 of the belt near one side of the table. The free end 19 of lever 17 extends outwardly beyond the opposite side of the table as clearly shown in FIG. 1. The lever is pivotally attached by means of a flexible sleeve element 21 of a durable fabric or similar material as that used for the belt, and is secured at one end thereof as by stitching 22 to the top surface 18 of the belt. The open end of sleeve element 21 receives a portion of lever 17, the sleeve opening being dimensioned in such a manner as to snugly receive lever 17 without the need for any securing means therefor.

A support means in the form of a short rod member 23 is provided for maintaining lever 17 and the upper torso of patient P in the desired angular position. Rod 23 is simply hinged to the lever's under surface as at lever 24 with its free end bearing against the top surface 18 of the belt during this propped up position of the lever.

In FIGS. 1 and 3, it can be seen that a pair of contiguous patient positioner devices 14 are used so that one of the devices nearest the patient's head, for example, may be propped up at a greater angle as compared to the other of such devices to effect and maintain a twist of the patient's spine while his hips are constrained during a catheterization procedure. Devices 14 are shown in FIG. 1 as designed for elevating the right shoulder of the patient although these devices can be also used as well for the left shoulder by simply arranging the device on the table in the manner as shown in phantom in FIG. 2. Moreover, should it become necessary to angularly position the patient's entire body, the devices 14 could be easily spaced apart with one of them positioned under the shoulder of the patient and the other positioned under his hips.

It should be pointed out that a chock block or the like could be provided in lieu of rod member 23 for the purpose of propping up lever 17 to a desired angular position.

It can be seen from the foregoing description that a simple and economical, yet highly effective, device is provided for conveniently moving all or a portion of the patient's body into a preferred angular position and maintaining it as such during some anatomical procedure. One or more of these devices may be used and positioned beneath various portions of the patient's body so as to raise one of his shoulders as described, one of his hips, a rib or some portion of the knee or even the head.

Obviously, many modifications and variations of the present invention are possible in the light of the above teachings. It is therefore to be understood that within the scope of the appended claims, the invention may be practiced otherwise than as specifically described.

I claim:

1. A device for raising a patient resting on the top surface of a table from a flat to an angular position for aiding in photographic and examination procedures, comprising at least one flexible belt secured about said table and having a top portion lying fully in contact against said top surface, at least one sleeve element attached at one end to said top portion near one side of said table, an elongated lever member located within said sleeve, the free end of said lever member extending outwardly of the other side of said table, and a lever

support means on said lever so that, as said free end is pivoted upwardly about said one end, said lever is maintained at a desired angular position for likewise angularly positioning the patient.

5 2. The device according to claim 1 wherein said lever support means comprises a rod member hingedly secured at one end to the undersurface of said lever member.

10 3. The device according to claim 1 wherein two of said flexible belts are provided, each said belt being secured about said table and each having a top portion lying fully in contact against said top surface, and wherein two of said elongated lever members are provided one for each said belt.
